COLUMBIA PLANOGRAPH CO., WASHINGTON, D. C.

UNITED STATES PATENT OFFICE.

EDWARD E. SIMPSON, OF OAKLAND, IOWA.

LADDER-SCAFFOLDING.

1,148,631.

Specification of Letters Patent. Patented Aug. 3, 1915.

Application filed September 26, 1914. Serial No. 863,717.

To all whom it may concern:

Be it known that I, EDWARD E. SIMPSON, a citizen of the United States, residing at Oakland, in the county of Pottawattamie 5 and State of Iowa, have invented certain new and useful Improvements in a Ladder-Scaffolding, of which the following is a specification, reference being had to the accompanying drawings.

10 My invention relates to certain new and useful improvements in scaffold attachments for use in connection with ladders and has for its objects to produce scaffold supports for attachment to ladders which shall be 15 economic of construction, readily secured in place and safe when in use, and with these ends in view my invention consists in the details of construction and arrangement hereinafter more fully set forth and as 20 illustrated in the drawing.

In order that those familiar with the art to which my invention appertains may fully understand my invention I will proceed to describe the same referring by numerals to 25 the accompanying drawing, in which—

Figure 1 is a perspective view illustrating a scaffolding produced by my attachments to a plurality of ladders. Fig. 2 is a plan view of one of the scaffold board supports and brace; Fig. 3 is a perspective view 30 of one of the devices by which the board support and the upper end of the brace are safely secured to the rounds of the ladder; and Fig. 4 is a side view of the rings employed to secure the devices shown at Fig. 35 in their proper and fixed relation with the scaffold board support and brace.

Similar reference numerals indicate like parts in the several figures of the drawing.

40 1, is intended to represent the front of a building against which two or more ordinary ladders 2 are supported at any angle suitable for the erection of a scaffold between them and the front of the building.

45 3 is a flat board support preferably of iron any suitable length and of such cross section as to provide the necessary strength and rigidity which is hinged at one end by a pintle bolt 4 and nut 5, to the bifurcated 50 end 6 of a strong metal brace 7 as clearly shown, and as will be obvious the support and brace may be readily connected or separated.

55 The free end of the support which is to be connected with a round of the ladder is provided with a series of orifices 8 at any

desired distance apart to provide for adjustment as will be presently explained, and the free end of the brace is also provided with any desired number of spaced orifices 9 for 60 a like purpose.

10 are the devices employed for securing the support and the brace to the rounds of a ladder and consist of preferably flat metal of suitable strength and dimensions and are 65 formed near one end with a seat 11 adapted to coincide with and embrace the underside of the round of a ladder and terminating in a round nipple or extension 12 adapted to be seated in any one of the orifices 8 or 9; 70 the shoulder 13 contacting with the underside of the brace and the support.

The nipple or extension 12 is projected at a slight angle to the main body in order that when placed in position to lock the support and the brace respectively to the rounds of the ladder, the free ends will be put under tension when drawn up against the underside of the support and brace and secured by elliptical or flattened rings 14, and thus the 80 round of the ladder will be tightly embraced.

In erecting a scaffold two or more ordinary long ladders are inclined against the building and with the support 3 and brace 7, hinged together as explained and shown, the upper end of a brace is secured upon a round of the ladder by passing the extension or nipple 12 of the device 10 through one of the orifices 9 then passing the device 90 under the round of the ladder and springing its free end into contact with the brace and locking it in place by sliding the ring 14 over the end, the end of the device being under tension will hold the ring in place, but if deemed necessary or expedient it may be secured in any other manner. The support 3 is now swung into horizontal position and its free end located upon the upper surface of a round of the ladder and secured 95 fixedly thereto by a device 10, as already explained with reference to the attachment of the brace. The ladders being suitably spaced to receive them, walking scaffold boards 15 are laid upon the supports 3, and if thought necessary secured against movement by removable bolts 16 passing through orifices 17 in the support.

By reference to Fig. 1 it will be seen that as the tops of the ladders are not sufficiently distant from the building for the scaffold 110 to be erected between the ladders and the

building as shown lower down, they may in the same manner as described be erected on the outside as shown in said figure.

From the construction shown and described it will be appreciated that scaffolding may be expeditiously erected and taken down, and all of the members constituting the supports and braces packed in a comparatively small compass.

10 Attention is especially called to the fact that by reason of the relation of the braces and supports when connected with spaced rounds of the ladder serve to stiffen the ladder and to prevent undue vibration of the

15 same.

I of course do not wish to be limited to any proportions or dimensions of the several referred to devices nor do I wish to be limited as to the material used although I prefer that they should be made of iron of suitable strength and rigidity.

What I claim as new and desire to secure by Letters Patent is:—

1. The combination with a brace having a longitudinal series of perforations, of a rung engaging clip coacting therewith comprising a straight body portion adapted to lie against the face of the brace, said clip being formed adjacent one end with a bowed rung seat and a reduced terminal portion adapted to be inserted through any one of the perforations in the brace and extending in a direction away from the direction of

the bowed seat and at an angle to the body of the clip, and means for detachably connecting the body of the clip against the face of the brace, the clip being adjustable along the brace to engage any one of said perforations to thereby adjust the operative length of the brace.

2. The combination with a brace for ladder brackets having a longitudinally extending series of perforations, of a rung engaging clip comprising a body portion adapted normally to lie against the face of said brace, said clip at one end being outwardly bowed away from the brace to form a rung engaging seat, the terminal end of the clip beyond said body portion being reduced in diameter and extended at an obtuse angle to the body of the clip and in a direction away from the direction in which the seat is bowed, said reduced portion being adapted for insertion through any one of said perforations whereby the operative length of the brace may be adjusted, and a locking ring sliding upon the brace and upon the body of the clip and normally holding the body of the clip in contact with the face of the brace.

In testimony whereof I hereunto affix my signature in the presence of two witnesses.

EDWARD E. SIMPSON.
